UNITED STATES PATENT OFFICE

LEON W. SLACK, OF TRENTON, NEW JERSEY, ASSIGNOR, BY MESNE ASSIGNMENTS, TO
RAZOR BLADE TILE, INCORPORATED

RAZOR BLADE DISCARD

Application filed November 5, 1928. Serial No. 317,239.

My invention relates to improvements in razor blade discard and it more especially consists of the features pointed out in the annexed claims.

The purpose of my invention is to provide a self-contained razor blade discard formed in the shape of a rectangular piece of porcelain having a rearwardly beveling foot; that has a downwardly inclined opening extending from the front face to the rear face; that on account of the rearwardly extending beveled foot the blades that are inserted through the opening will always be delivered past the thickness of the plastering in which the razor blade discard is fastened; and that lends itself to installation with ordinary conventional tiling.

With these and other ends in view I illustrate in the accompanying drawings such instances of adaptation as will disclose the broad underlying principles of my invention, without limiting myself to the specific details shown thereon and described herein.

Figure 1 is a perspective view showing the front of the discard.

Fig. 2 is a rear elevation in perspective.

Fig. 3 is an elevation in section showing the discard secured in a wall.

Fig. 4 is a rear elevation.

In practically carrying my invention into use I may employ whatever alternatives of construction that the exigencies of varying conditions may demand without departing from the broad spirit of my invention.

The discard consists substantially of a molded piece of porcelain 4 which is of the same thickness as an ordinary tile. It has a front opening 5 with a lower edge lip 8 and a rearward downwardly extending upper face 6 which terminates in the rear lip 9 above the opening 7. The upper edge 15 and the lower edge 14 as well as the side edges abut against the adjacent tiles. The lower edge 14 extends rearwardly at 12 as a beveled foot 10. On the rear face two projections 13

are formed to assist in holding the fixture in the plaster 1 of a wall adjacent the wall opening 2.

It will be noted from Fig. 3 that the opening 5 slopes downward but does not continue at the same angle all the way to the foot 12 because when partly through the thickness of the fixture a change into the bevel 11 is made. As already stated the fixture is secured in any suitable wall alongside of and flush with adjacently placed tiles 3.

It will be readily seen that the opening through the fixture in a downward direction assists in causing the discarded razor blades to effectually slide through the wall without becoming lodged on any portion of plaster that may project at that point. This fixture makes it possible to prevent the throwing of waste razor blades into paper baskets, etc., where they are liable to cause injury to caretakers. By placing the razor blades through the opening into the open space of the inner wall they there become oxidized and gradually disintegrate.

What I claim is:

1. A tile adapted to receive discarded razor blades comprising a beveled rearwardly extending foot, beveled faces extending across and below an opening formed through the tiling, and an inclined bevel leading from the opening onto the rearwardly extending foot.

2. A tile adapted to receive discarded razor blades having a downwardly extending opening through its body, a rearwardly extending foot, and a beveled upper face of the foot which joins the lower beveled face of the tiling.

3. A bathroom fixture adapted to surround an opening extending downwardly toward the rear of the fixture, a beveled extension of the lower surface of the opening projecting rearward from the rear face of the fixture, and a rearwardly projecting foot from the lower edge.

4. A bathroom unitary fixture adapted to

become associated on a wall with adjacently placed conventional tiles, means for holding the fixture opposite an opening in the wall, a pair of sloping surfaces defining a downwardly extending slotted opening through the fixture, and a rearwardly extending portion whose upper surface is a downward continuation of the lower surface of the fixture opening.

10 In testimony whereof I affix my signature.
LEON W. SLACK.
